(57) **CLAIM**

The ornamental design for a multifunctional pineapple cutter with knife, as shown and described.

DESCRIPTION

FIG. 1 is a front, right and top perspective view of a multifunctional pineapple cutter with knife in a disassembled state, showing my design.

FIG. 2 is a rear, left and bottom perspective view thereof. FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 2.

FIG. 10 is another front, right and top perspective view of the multifunctional pineapple cutter with knife in an assembled state; and,

FIG. 11 is another rear, left and bottom perspective view of the multifunctional pineapple cutter with knife in an assembled state.

The broken lines depict portions of the multifunctional pineapple cutter with knife that form no part of the claimed design. In addition, the dot-dash broken lines in FIGS. 2 and 9 depict the boundaries of the enlargements that form no part of the claimed design.
